UNITED STATES PATENT OFFICE.

PAUL T. HERTZOG, OF NEWARK, NEW JERSEY, ASSIGNOR TO HEILNER & STRAUSS, OF NEW YORK, N. Y.

DESIGN FOR A CORSET.

SPECIFICATION forming part of Design No. 17,242, dated April 5, 1887.

Application filed February 7, 1887. Serial No. 226,974. Term of patent 3½ years.

To all whom it may concern:

Be it known that I, PAUL T. HERTZOG, a citizen of the United States, residing at Newark, county of Essex, State of New Jersey, have invented and produced a new and original Design for Corsets, of which the following is a specification, reference being had to the accompanying drawing, forming part hereof.

My design consists of a corset which presents at its waist-line a corded, corrugated, or wavy appearance, said lines of ornamentation extending from the front to the lacing-holes at the back, or from near one of those points to near the other, in each half of the corset, said lines of ornamentation as an entirety presenting a configuration substantially as shown in the drawing.

The drawing shows a front view of one-half of the corset containing my design.

20 *a* is the front steel; *b*, the back or lacing holes. *d d*, &c., are pockets.

e is the top of the corset, which may be ornamented or otherwise.

f is the bottom of the corset.

25 *g* is the belt, which on its upper edge has a slight curve from its center to its outer edges upward. This curve is so slight that when the corset is held in the flat position shown in the drawing it has the appearance of nearly a straight line, and on its bottom edge the belt presents the appearance of a double-curved line, beginning at or near the front, near the bottom thereof, and running thence upward toward the waist-line, curving again in a

slightly-downward direction toward the lacing-holes. 35

g' are lines of ornamentation parallel to each other on the belt.

I claim—

1. The design for a corset herein shown and described, which consists of a corset having a belt at its waist-line which presents a corded, corrugated, or wavy appearance, said belt on its upper edge following substantially a line parallel with the waist-line of the corset, and at its lower edge following a line beginning at the front of the corset, near the bottom thereof, then running in an upwardly-inclined direction toward the waist-line and back of the corset, and thence toward the back of the corset, substantially as described. 40

2. The design for a corset herein shown and described, which consists of a corset having a belt at its waist-line which presents a corded, corrugated, or wavy appearance, said belt on its upper edge following substantially a line parallel with the waist-line of the corset, and at its lower edge following a line beginning at the front of the corset, near the bottom thereof, then running in an upwardly-inclined direction toward the waist-line and back of the corset, and thence toward the back of the corset, said belt having its surface crossed by the stay-pockets *d d*, &c., substantially as described. 55

P. T. HERTZOG.
